UNITED STATES PATENT OFFICE.

WALTER E. BARNARD, OF HARTFORD, CONNECTICUT, ASSIGNOR TO UNDERWOOD
TYPEWRITER COMPANY, OF NEW YORK, N. Y., A CORPORATION OF DELAWARE.

TYPE-WRITING MACHINE.

1,073,083.

Specification of Letters Patent. Patented Sept. 16, 1913.

Application filed September 17, 1910. Serial No. 582,443.

To all whom it may concern:

Be it known that I, WALTER E. BARNARD, a citizen of the United States, residing in Hartford, in the county of Hartford and State of Connecticut, have invented certain new and useful Improvements in Type-Writing Machines, of which the following is a specification.

This invention relates to line-space mechanisms, and one object thereof is to provide improved and simplified means to arrest the platen at the end of the line-space stroke. I provide a lever, one arm of which is struck preferably by the line-spacing pawl to cause the opposite arm of the lever to press the usual detent forcibly against the line-space wheel, to arrest the latter and the platen.

Another feature of the invention is to restore automatically the control of the spring detent over the platen, after said detent has been locked away from the line-space wheel. This is preferably also done by the line-spacing pawl. Preferably a single arm engaged by the line-spacing pawl both restores the detent, (if it be in abnormal position), and finally forces said detent into a notch of the line-space wheel.

In the accompanying drawings, Figure 1 is a side view, showing one form of the invention applied to the platen frame of an Underwood writing machine, the detent being cast off. Fig. 2 is a detail perspective of the combined detent-releasing and platen-arresting lever. Fig. 3 shows the line-spacing pawl arrested by the stop arm, the detent having been returned to operative position. Fig. 4 is an enlarged detail, showing the lever between its extreme positions. Fig. 5 is a detail perspective of the line-spacing pawl. Fig. 6 is like Fig. 4, but showing the platen arrested at the completion of the line-spacing action.

Types 1^a strike a platen 1, mounted on an axle 2, journaled in the ends 3 of a platen frame. A lever 4 drives a slide 5, carrying a pawl 6 having a tooth portion 7 to engage a notched wheel or ratchet 8 fixed on the axle 2. The lever, slide and pawl constitute means to drive the wheel, the slide and pawl forming a driving device movable into direct driving engagement with the wheel. A spring detent 9, pivoted at 10, engages the wheel, said detent having a roll 11 to seat in any of the notches of said wheel to hold the platen. A shoulder 13 on the pawl

strikes one arm 14 of a lever, (having a hub 15 supported loosely on the hub 16 of the wheel 8); the opposite arm 17 of the lever being hooked to catch over a pin 18 usually provided on the detent 9, (Fig. 4), and force the detent into a notch of the wheel 8. For this purpose, one edge of the hook may form a cam 19, which presses the detent roll 11 forcibly into the notch. This action of the detent occurs at the moment when the wheel 8 has been turned by the pawl 7 to bring one of its notches in register with the detent roll. By this means overthrow of the platen is prevented; the continued pressure on the lever 4 tending to force the detent or stop-roll 11 more powerfully into the notch.

The lever 14, 17, may be a modification of the usual detent-releasing lever, which commonly has on the outer end of arm 17, a cam 20 to engage the pin 18 to force the detent away from the wheel, the lever having a handle 21 for this purpose. A dwell portion 22 on the cam 20 usually locks the detent away from the wheel. A stop 23 is usually provided on the lever. Depression of the handle 21 releases the pin 18 from the cam, whereupon the control of the spring detent over the wheel 8 is restored.

In case the operator forgets to release the detent, its restoration is automatically effected by contact of the line-spacing pawl, or its shoulder 13 with the stop arm 14 which is of such construction, that when the lever 14, 17 is rocked to hold the detent idle, as in Fig. 1, the arm is swung forwardly in position to be struck by the shoulder 13 of the line-spacing pawl.

Having thus described my invention, I claim:

1. In a typewriting machine, the combination with a platen ratchet, a pawl, and a detent normally engaging the ratchet, of a cam to press the detent into a notch in the ratchet, and an arm struck by the pawl to operate the cam.
2. In a typewriting machine, the combination with a platen and line-space mechanism therefor including a platen ratchet and a pawl, of a detent seating in a notch in the ratchet, and a member operatively engaging the detent and intermittently engaged by the pawl of the line-spacing mechanism to press the detent into its notch.
3. In a typewriting machine, the combi-

nation with a platen ratchet wheel, of a detent to engage said ratchet wheel, a lever pivoted upon the axis of the ratchet wheel and including an arm to press said detent into the notches of the wheel, and a pawl to drive said wheel for line-spacing, said lever also including an arm to be operated by said driving pawl.

4. In a typewriting machine, the combination with a platen ratchet wheel and a spring pressed detent therefor, of a line-spacing pawl to engage said ratchet wheel, a lever having an arm engaged by said pawl, and another arm engaging said detent to force the same into the notches of the ratchet wheel.

5. In a typewriting machine, the combination with a line-spacing wheel, of a spring detent for the wheel, a device movable to release said detent and hold it released, a pawl for said line-spacing wheel, and means to enable said pawl to return said releasing device.

6. In a typewriting machine, the combination with a line-space ratchet wheel, a pawl, and a spring pressed detent engaging the wheel, of a lever to cast off the detent and hold it ineffective, said lever having a part in the path of said pawl to enable the latter to return the lever to normal position, and means on said lever to enable said pawl to press the detent into the notches of the wheel.

7. In a typewriting machine, the combination with a line-space ratchet, of a detent

normally held in engagement with the ratchet by spring pressure, means to cast off the detent and hold it ineffective, and a line-spacing pawl provided with means to restore said detent and force it into a notch 40 of said ratchet.

8. In a typewriting machine, the combination with a line spacing ratchet, a spring pressed detent for the ratchet, a pawl for said ratchet, a lever having a cam surface 45 to release said detent, and a cam surface to positively move said detent into engagement with said ratchet, of means on the pawl to move said lever to engage said detent with said ratchet as it turns the ratchet in line-spacing direction.

9. In a typewriting machine, the combination of a platen having an axle, a line-spacing ratchet, a pawl therefor, a detent for said ratchet, and a lever pivotally 55 mounted on the platen axle and having means to release said detent, and engageable by said pawl to restore said detent.

10. In a typewriting machine, the combination with a line-space ratchet, of a detent 50 normally held in engagement with the ratchet by spring pressure, means to cast off the detent and hold it ineffective, and a line-spacing pawl provided with means to restore said detent and apply a holding pressure thereto.

WALTER E. BARNARD.
